UNITED STATES PATENT OFFICE.

CLARE E. PANCOST, OF CINCINNATI, OHIO, ASSIGNOR TO THE ROYER WHEEL COMPANY, OF SAME PLACE.

DESIGN FOR A HUB-BAND.

SPECIFICATION forming part of Design No. 28,400, dated March 22, 1898.

Application filed November 30, 1896. Serial No. 614,004. Term of patent 7 years.

To all whom it may concern:

Be it known that I, CLARE E. PANCOST, a citizen of the United States, residing at Cincinnati, in the county of Hamilton and State of Ohio, have invented and produced a new and original Design for Vehicle Hub Bands or Shells, of which the following is a specification, reference being had to the accompanying drawing, showing a part thereof.

- The figure is a perspective view of my newly designed hub-band.

Heretofore hub-flanges have been made which present, when viewed in perspective, as in the figure, an extension which extends out flush with the end of the hub. Some are smooth and some are checkered by diagonal grooves crossing each other. In this flange the extension A extends out flush with the end of the hub which it incloses, and the outer

surface is grooved or corrugated and leaves a rough projection in the space between the grooves.

The leading features of my design consist in a flat circular flange B, a tapering portion C, which corresponds with the contour of the usual tapering portion of the hub of a wheel, and the cylindrical extension A, the outer surface of which is grooved laterally, leaving rough projections between the grooves.

Having described my new design, what I claim as my invention, and desire to secure by Letters Patent, is—

The design for a hub band or shell, substantially as herein described and shown.

CLARE E. PANCOST.
